BATTEN CLAMP

Onésime Lamothe, Champlain, Quebec, and
 Joseph Albert Lamothe, Lachine, Quebec,
 Canada

Application May 23, 1945, Serial No. 595,286

1 Claim. (Cl. 292—140)

1

The present invention relates to an adjustable clamp and, more particularly, such a clamp for retaining in place the tarpaulin-securing battens of ship hatches.

The primary object of the invention, therefore, resides in the provision of batten-retaining means for ship hatches which are highly efficient and reliable for the purpose in view.

Another object is the provision of means of the character defined, which can be brought rapidly in action even under adverse climatic conditions.

Another object contemplates batten-retaining means which are easily operable with a minimum of simple tools.

A further object envisages batten clamps for ship hatches which are relatively inexpensive, easy to manufacture and adapted to operate safely for long periods of time.

Other objects and advantages of the invention will become apparent, or be pointed out further, during the description to follow.

As an example, and for purposes of illustration only, two embodiments of the invention are shown in the annexed drawings, wherein:

Figure 1 is a perspective view of a corner of a hatch showing the clamps in use.

Figure 2 is a side view of the type of clamp shown in Figure 1.

Figure 3 is an horizontal section taken on line 3—3 of Figure 2.

Figure 4 is a perspective view of the batten-engaging bolt.

Figure 5 is a vertical section through the clamp showing the bolt in extended position.

Figure 6 is a similar view but with the bolt retracted.

Figure 7 is a side view similar to Figure 2 but showing a modified clamp secured to the side of the hatch, and

Figure 8 is a front elevation of the clamp shown in Figure 7.

Referring to the drawings, wherein similar reference characters represent corresponding parts throughout, the reference letter D indicates generally the deck of a ship, and above which deck the hatch sides H extend vertically, as usual. The said sides, when the hatch is being closed, support the boards or planks P over which the canvas or tarpaulin T is disposed. The battens B are the strips for securing the downward edges of the tarpaulin against leakage.

As shown in Figure 1, the battened hatch has disposed therearound a plurality of clamps according to the invention, which clamps are represented generally by the letter C, the purpose of

2

said clamps being to press the battens securely in place.

Briefly described, the clamp of the invention consists of a frame or body in which a bolt is 5 slidable, said bolt being pressed against the batten by means of an eccentric cam operated by a suitable tool such as a spanner, wrench or the like. Said cam is provided with undulations which, in combination with a suitable notch in the bolt, are 10 adapted to retain its position against vibration, shocks and the like. A second smaller cam is also used to retract the bolt when the main cam is released, so as to free the bolt from salt incrustations, ice and the like.

15 The body of the clamp B is a block affecting a general rectangular shape and the front part of which is hollowed out so that an upper tongue 5 and lower tongue 6, both disposed in parallel position, project forwardly from the back of said body which is solid to the exception of a square aperture 7 formed therein to receive the bolt 8. Ears 10 are also formed sideways from the lower part of the body and serve to secure the clamp to the deck D by means of the rivets 11 or the like.

20 The bolt shown in Figure 4 includes the bolt proper 8 slidable in the aperture 7 and provided with a flat extension 12 provided at the outer end with an upturned flange 13, the inside curvature of which is made to conform with an auxiliary 25 retracting cam to be described later. The said extension has a longitudinal elongated slot 14 and a vertical V-shaped notch 15 in the rear face thereof, the purpose of which will be described also.

25 The means for actuating the bolt, or pressing said bolt against the batten, consists of a cam 17 of substantially circular cross-section and provided on the periphery thereof with a series of 30 vertical concave depressions 18, the meeting points of which forming ridges or ribs 19 adapted 35 to engage the notch 15 of the bolt so as to lock the cam in place. A stop is provided in the form of a spur or projection 20, which is normally higher than the ribs 19. The said bolt-actuating

40 cam is adapted to be disposed between the tongues 5 and 6, at the forward end thereof, so as 45 to be rotated therein by means of a special pin 22 including a square head 23, a shoulder 24 fitting in a suitable round aperture of the upper tongue 5, a square shank 25 which enters a similar square bore formed eccentrically with respect 50 to the periphery of the cam and which pin extends at its lower end through the lower tongue 6 in a suitable aperture concentric with that of the upper tongue. A cotter pin or the like ele-

ment 26 is provided to prevent withdrawal of the pin 22.

As shown to advantage in Figures 5 and 6, the bottom of the cam 17 is reduced to form an auxiliary retracting cam 28 shaped to correspond with the contour of the main cam and engaging the upturned curved flange 13 of the bolt 8. Thus, the said bolt can be retracted positively by the auxiliary cam acting on the curved flange. Due to the fact that the pin 22 enters the slot 14 of the extension 12, said pin acts as a guide to prevent lateral movement of the extension and, consequently, an improper functioning of the cam 28.

The modified form shown in Figures 7 and 8 is very substantially the same as that just described to the exception of the means for mounting the clamp onto the side of the hatch proper instead of on the deck. For that purpose, a bracket is cast integral with the body, on the underside thereof, and includes ears 30 formed as integral lateral extensions of the flange 31 depending downwardly from the rear of the clamp body and braced to the forward part thereof by means of the web 32. Rivets or the like 33 are used to secure the ears to the hatch.

The clamps just described are operated by engaging the square head of the pin 22 and turning the same clockwise for expelling the bolt outwardly. Inasmuch as the main operating cam is eccentrically mounted on the shank of the pin, the said rotation of the pin will cause the cam to force the bolt against the batten. Further rotation of the pin will eventually press the said bolt strongly against said batten, the ribs of the cam engaging the notch on the inner face of the bolt. As previously stated, the combination of the rib and notch acts as a lock to prevent accidental loosening of the cam by vibration, shock or the like.

The smaller auxiliary retracting cam, is used solely for retracting the bolt should said last become wedged in the body by stalks, rock or ice. Normally, the resiliency of the canvas tarpaulin between the batten and the hatch 5 is sufficient to permit loosening the bolt by the simple expedient of rotating the pin counter-clockwise; however, when it is desired to retract the bolt further inward, the auxiliary cam is obviously of great use.

From the preceding description it should be evident that the present invention is an advance of the art in that it enables the rapid and safe

battening of hatches, even under adverse conditions. Since no loose parts are used, in contrast to the old style of wedges, sledged in place, the clamp of the invention is a distinct improvement since all that is necessary to batten the hatch is a spanner or the like for operation of the pin. In adverse conditions such as icing of the ship in cold weather, the present clamp can still be actuated easily, since any ice formed on the clamp can be easily broken until the head of the operating pin can be reached; thereafter, the cam can be easily rotated, since it clears itself of ice or other accumulation, with comparative ease.

15 It must be understood that various changes as to the size, shape and arrangement of parts can be resorted to without departing from the spirit of the invention or the scope of the subjoined claim.

20 Having thus described our invention, we claim:
In batten-clamping means, a body, a batten-engaging bolt slidable in said body, spaced parallel tongues extending from one end of said body, a corrugated cam rotatably mounted between said tongues having a periphery engageable with the bolt to positively slide the latter, notch means on the cam-engaging surface of the bolt for disengageably securing the corrugated cam in locked position, an auxiliary bolt-retracting cam formed on said first cam, an extension on the bolt for engagement by the auxiliary cam, and a rotatable pin for actuating both cams for extending the bolt and retracting same.

35 ONÉSIME LAMOTHE.
JOSEPH ALBERT LAMOTHE.
